CLOTH BOARD AND METHOD FOR MAKING SAME

Norman Karp, 106 Lincoln Parkway,
Lowell, Mass. 01851
Filed June 3, 1964, Ser. No. 372,223
7 Claims. (Cl. 206—50)

This invention relates to an improved cloth board of the doubled roll reel type and an improved method for making the same.

It has heretofore been proposed to make such cloth boards of a single thickness of material, but to build up the thickness of each end by various expedients such as separate, individual end strips or by attaching a hollow end piece. For example, in U.S. Patent 1,899,195 to Heath of Feb. 28, 1933 a single ply body of solid paperboard is provided with a superposed, narrow strip at each end, secured in place to form a substantial thickness and a label is secured on the upper and lower faces of the built-up end portions.

Devices of this type are disposable and reduction of cost of manufacture together with reduction of cost of materials are of extreme importance in the art. The various devices shown in prior patents or presently in use for the purpose have certain disadvantages especially in the wastage of material in forming the parts and in the relatively high cost of the parts. As far as I am aware, the trade presently makes much use of two superposed plies of corrugated paperboard, connected at each end by a glued, folded label, as a disposable doubled roll reel and does not make much use of other types of reel.

In this invention the principal object is to provide a reel made from a single ply of corrugated paperboard having single ply exposed side edges but having thickened ends by reason of integral, hingedly-connected, end flaps slit, but not severed, from the single plies folded back over the ends of the single ply and held in place by a layer of adhesive and preferably by other securing means. The structure of the invention thus not only eliminates the cost of a second ply of material, thereby reducing the requisite amount of board needed for each reel by at least twenty-five percent, but the end flaps are slit from the single ply itself and cannot be misjoined, disoriented or likely to slip with relation to the main body.

Another object of the invention is to provide a unitary, low cost cloth board formed from a rectangular, over length blank of corrugated paperboard having longitudinal side edge free of doubling or folds, wherein the flutes run longitudinally of a single thickness of the board and each end is thickened by at least one integral, folded end flap slit from, and overfolded onto the board and securely affixed thereto.

A further object of the invention is to provide a method for making low cost doubled roll reels wherein a single ply, rectangular blank of corrugated paperboard is transversely slit at each end to form foldable end flaps, the flaps are overfolded to form multi ply ends on the board and the flaps are secured in place by means such as a hot melt adhesive and then at least partially covered by a foldable end label.

Other objects and advantages of the invention will be apparent from the claims, the description of the drawing and from the drawing in which:

FIG. 1 is a perspective view of a doubled roll reel constructed in accordance with the invention.

FIG. 2 is a side elevation showing the step of slitting a single ply of corrugated board to form foldable, hingedly connected end flaps.

FIG. 3 is a view similar to FIG. 2 showing the end flaps overfolded, adhered and partially covered by the end labels.

2

FIG. 4 is a view similar to FIG. 3 showing the end flaps overfolded, adhered and entirely covered by the end labels.

FIG. 5 is a view similar to FIG. 2 showing an embodiment in which two end flaps are oppositely slit at each end of the board, and

FIG. 6 is a view similar to FIG. 3 showing the board of FIG. 4, folded, adhered and covered at each end to form three plies.

A preferred embodiment of the invention is shown in

10 FIG. 1 wherein the doubled roll reel 20 is formed of low cost corrugated paperboard material 21, in a single ply. The material 21 includes an upper liner 22, a lower liner 23 and the flutes 24, which preferably extend longitudinally of the main body 25 of the reel. In the device illustrated 15 the corrugated material includes two sets of flutes, separated by a liner but it will be apparent that any of the conventional corrugated boards may be used, which have both upper and lower liners. As shown in the drawing the blank 27 is flat and rectangular with two opposite, longer 20 sides and two opposite, shorter sides, or ends, the side and end edges being single ply and exposing the flutes in the usual manner of sheets cut from corrugated paper-board.

The blank 27 is several inches longer than the final 25 product, and formed of a single ply of material 21. As shown in FIGURE 2, the first and critical step is the slitting of the blank, along lines parallel to and spaced inwardly from the ends 28 and 29, from the outside face 31 of one liner 23 to the inside face 32 of the other liner 22.

30 The knives 33 and 34, or other suitable cutting or scoring device, thus form the slit lines 35 and 36 which in turn define fold lines 37 and 38 for the resulting foldable end flaps 40 and 41, connected by webs of the upper liner 22 while still integral with the main body 25. In subsequent 35 glueing, folding and covering steps control of the end flaps is not lost and the overfolded flaps are exactly positioned because of the hinge connection at the web along the fold lines 37 and 38.

As shown in FIGURE 2 the next step in making the 40 reel 20 is the application of a layer of adhesive 42 and 43 along the outer face 44 of the upper liner 22 of body 25, in the area which will be occupied by the end flaps 40 and 41, when overfolded. Preferably the adhesive 42 and 43 is of the hot melt type, such as Thermogrip, a product of 45 United Shoe Machinery Corp. of Beverly, Massachusetts, and may be applied by any suitable adhesive applying means as the slit blanks 27 are advanced along the paper line of a folding and glueing machine of conventional type.

The end flaps 40 and 41 are then overfolded through 50 an angle of 180° on the fold line 37 or 38 into superposed position overlying the adjacent portion of the face 44 and overlying the adhesive strips 42 or 43, so that ends of double thickness are formed. When the end flaps 40 and 55 41 are overfolded, the cut flutes and liners along the slit liner 35 and 36 are exposed. The adhesive 42 and 43 secures the flaps in folded position while the blanks 27 are advanced along the paper line of a folding machine and until the final step of applying the end covering labels 46 and 47 is completed.

60 As shown in FIGURE 3, each end label such as 46 is formed of foldable paper, sheet material such as cardboard 48, precreased along lines 50 and 51 to fit over the ends of the reels. Staples 49, rivets or similar means, 65 may be used to hold the end labels 46 in place.

As shown in FIGURE 4 end labels 47 are formed of thin, low cost, foldable sheet material such as cardboard 48, pre-creased along lines 50, 51, 52, and 53 to snugly fit over, and cover the exposed, slit, flutes and double ply 70 ends of the reel. The entire inner face 54 of each label 46 or 47 may be covered with a layer of adhesive so that the panels of the labels, defined by the crease lines will

adhere to the corresponding faces of the corrugated board.

However the terminal ends 55 and 56 of the label 47 extend inwardly along the main body 25 and are adhered by a layer of adhesive at 57 and 58 to the faces 44 and 31 to not only cover the ends but also to keep the flaps overfolded in cooperation with the hot melt adhesive 42 or 43.

As shown in FIGURES 5 and 6, a blank 60 similar to blank 27, may be slit along two lines 61 and 62 at each opposite end, by knives 63 and 64 from opposite directions, to form end flaps 65 and 66, corresponding to the flaps 40 and 41, and an additional end flap 67 or 68 at each end of the reel.

Two layers of hot melt adhesive 69 and 70 are applied as shown, and the two end flaps such as 65 and 68 at each end are folded as shown on their integral webs 72 and 73 to form multi ply ends of triple thickness. Each pre-creased end label, such as 74, has its terminal ends 76 and 77 adhered to the main body 78 of the resulting reel 80 in the same manner as described above.

I claim:

1. A cloth winding board of the doubled roll reel type, said board comprising:

an elongated, single ply rectangular strip of corrugated paperboard having a pair of opposite, longer, single ply, sides, free of doubling and folds, a pair of opposite, shorter ends, said paperboard including an upper liner and a lower liner, and flutes extending longitudinally from end to end thereof, in parallelism with said longer sides;

said strip being slit along lines parallel to, and equally spaced inwardly from said ends, and said slits extending from the outer face of one said liner to the inner face of the other said liner to define a pair of integral, hingedly-connected, slit; end flaps;

said end flaps being overfolded along the line of said slits to overlie said strip and form relatively thick ends thereon, with the slit lines of said strip exposed; a layer of adhesive bonding each said flap to the adjacent face of said strip;

a pair of pre-creased, paper labels, each folded around one of said relatively thick ends and at least partially covering the same while entirely covering said exposed slit lines;

and means affixing said labels in said position on said ends.

2. A cloth winding board as specified in claim 1 wherein:

each said label includes oppositely disposed, terminal portions each overlying and engaging one of said liners inwardly from the adjacent relatively thick ends;

adhesive means adhesively securing said terminal portions to said liners.

3. An improved doubled roll reel comprising:

an elongated, rectangular, single ply body of fluted corrugated paperboard, said body having two opposite longer sides with single ply edges free of folds and two opposite shorter ends, said body being partially slit along lines parallel to, and spaced inwardly from, each said opposite end thereof to define a pair of oppositely disposed, hingedly-connected end flaps; said end flaps being overfolded on said lines to form a double ply at each end of said single ply body;

a pre-creased paper end label at least partially covering each said double ply end; and

means securing said labels and flaps to said single ply body.

4. An improved doubled roll reel comprising:

a single ply rectangular blank of corrugated paperboard having opposite longitudinal edges, free of folds, flutes extending in parallelism with said longitudinal edges and opposite lateral edges;

said rectangular blank being slit laterally proximate

each opposite lateral edge thereof to divide said blank into a single ply main body and at least one hingedly connected, integral end flap folded back into superposed position on said body at each opposite end thereof to form multi ply ends thereon; a layer of adhesive bonding the said multi plies to each other and to said body; and

a pre-creased paper label folded over each said multi ply end and covering the same, the terminal portions of said label being adhered to the opposite faces of said single ply main body.

5. The method of making a doubled roll reel from a single ply of corrugated paperboard which comprises the steps of:

forming a flat rectangular blank from said corrugated paperboard with a pair of opposite shorter ends and a pair of opposite longer sides of greater length than desired, the side and end edges of said blank being free of folds and exposing the flutes of said paperboard;

slitting said blank along transverse lines proximate, and parallel to, each opposite end from the outside face of one liner to the inside face of the other liner to form a single ply main body of the desired length with a pair of integral, opposite hingedly connected, foldable end flaps;

then applying a layer of adhesive to said board in position to adhere said flaps in overfolded position; and then overfolding said end flaps through an angle of 180° into adhered position overlying said main body to form multi ply, integral ends thereon.

6. A method as specified in claim 5, plus the step of: pre-creasing a pair of end labels to each define a plurality of panels adapted to overlie one of the said multi ply integral ends of said reel; and securing one said end label over each opposite multi ply end of said board to at least partially cover the same.

7. A cloth winding board of the doubled roll reel type comprising:

an elongated, single strip of corrugated paperboard including an upper liner and a lower liner, and flutes extending longitudinally from end to end thereof; said strip being slit along two parallel lines at each said end, said two slits being each from an opposite direction and each slit extending from the outer face of one said liner to the inner face of the other said liner, to define a pair of integral, hingedly-connected, end flaps at each end of said strip;

the inner end flap at each end being overfolded along the line of the inner slit to overlie said strip and the outer end flap at each end being overfolded along the line of the outer slit to overlie said inner flap to thereby form relatively thick ends of triple thickness on said strip;

a layer of adhesive bonding each said overfolded outer flap to the adjacent inner flap and a layer of adhesive bonding each said inner flap to the adjacent face of said strip;

a pair of labels each folded around one of said ends of triple thickness and at least partially covering the same; and

means affixing said labels in said position on said ends.
